UNITED STATES PATENT OFFICE.

FREDERICK P. MARX, OF ST. LOUIS, MISSOURI.

SHOE-HEEL.

1,356,727.

Specification of Letters Patent.

Patented Oct. 26, 1920.

Application filed December 19, 1919. Serial No. 346,089.

To all whom it may concern:

Be it known that I, FREDERICK P. MARX, a citizen of the United States, residing at St. Louis, Missouri, have invented a new and useful Shoe-Heel, of which the following is a specification.

This invention relates to shoe heels.

An object of the invention is to provide an improvement in the art of shoe heels whereby the shoe heel may be provided with a leather cover that is perfectly smooth and devoid of folds or creases.

Heels for ladies' shoes are formed with curved walls or surfaces which converge downwardly from the top of the heel to a point somewhat above the bottom of the heel, and from that point to the walls or surfaces of the heels, diverge to the bottom of the heel. Difficulty has been encountered in providing these heels with leather covers, due to the peculiar curved walls or surfaces of the heels. It is desirable that the leather covers be perfectly smooth throughout the surfaces of the heels so that there will be no folds or creases in the leather. By my invention this desirable result can be accomplished.

Difficulty has been encountered in making the heels strong enough at the smallest parts thereof, and I overcome this difficulty by making a metallic heel body which is strong enough for all practical purposes, and which is provided with an ornamental cover. The heel body is also provided with an improved means of attachment to a shoe, and with an ornamental vanity ring between the separate parts of the cover.

Figure 1 is a plan view of a heel constructed in accordance with my present invention.

Fig. 2 is a side elevation of the heel with portions of the leather cover removed.

Fig. 3 is a rear elevation of the heel with portions of the leather cover removed.

Fig. 4 is a front elevation of the heel.

As shown, the heel comprises a metallic body 1 which may be aluminum, or other suitable metal or alloy. Preferably, the heel body has a penetrable block 2 of wood or other appropriate material, secured in the upper forward and central portion thereof to receive fastening elements by which the heel is secured to the shoe.

A prong 3 is formed in rigid or integral connection with the upper wall of the heel,

near the rear edge thereof to serve as a part of the fastening means by which the heel is secured to the shoe.

As shown, the rear wall slopes or inclines downwardly and forwardly from the top of the heel; said rear wall being rounded and forming side walls which converge downwardly and inwardly from the top of the heel; and the front wall of the heel is formed on a curve beginning at the forward upper edge of the heel and extending in an irregular curved line to the bottom of the heel. From a point somewhat above the bottom of the heel, the side walls and the rounded rear wall of the heel diverge or flare outwardly to form a base for the heel, having greater width and length than the narrowest part of the heel which is somewhat above the base. At or about the narrowest part of the heel, somewhat above the base thereof, a metal vanity or ornamental ring 4 is provided in rigid or integral connection with the heel, said ring having a radial thickness equal to the thickness of the leather by which the heel is covered. The ring 4 extends around the rear and side walls of the heel but does not extend across the front side of the heel.

My invention also comprises the provision of the section 5 of leather cut to fit against the rear and side walls of the heel from the top of the heel to the narrowest portion of the heel, bordered by the vanity ring 4. This piece of leather is cut to permit its upper edge 6 to be folded over the top of the heel so as to be compressed between the heel body and the heel portion of the shoe sole.

I do not encounter difficulty in securing a piece of leather to the heel without forming folds or wrinkles, when the lower edge of the leather terminates at the narrowest part of the heel and against the upper edge of the vanity ring 4. The lower portion of the heel comprising that portion which is below the vanity ring 4 is inclosed within a leather cover 7 cut to fit around the flaring lower portion of the heel, with the exception that said section 7 does not extend across the front of the heel nor entirely cover the bottom wall of the heel. The edges 8 of the section 7 are folded under the heel body adjacent to the edge thereof.

The front wall of the heel is covered by a single piece of leather 9 having its side

edges terminating at the side edges of the front wall and covered by the sections 5 and 7 so that the raw edges of the section 9 are invisible.

5 From the foregoing description, it will be apparent that my invention completely and satisfactorily attains its object. The heel is provided with a leather cover which is perfectly smooth throughout, which is 10 wholly free from folds and wrinkles, and which will retain its connection with the heel under all ordinary conditions. The leather sections may be glued or otherwise satisfactorily secured to the heel. Moreover, the 15 heel may be formed with a smaller body at its reduced portion, without danger of breaking, and the pressure of the penetrable block 2 permits the heel to be fastened to the shoe by means of nails or the like. The 20 heel can be accurately positioned, which is a serious difficulty in the case of metallic heels having holes in the metal to receive the fasteners.

What I claim and desire to secure by Letters Patent is:

1. A shoe heel of the character described comprising a heel body having a portion thereof between its upper and lower ends narrower than the upper and lower portions 30 of the body; a vanity ring in connection with the narrow portion of the heel body extending upwardly therefrom; a section of leather glued to the rear and side walls of the heel body above the vanity ring and 35 having its lower edge terminating at the vanity ring; and a separate section of leather secured to the rear and side walls of the heel body below the vanity ring.

2. A shoe heel of the character described 40 comprising a heel body having a portion thereof between its upper and lower ends narrower than the upper and lower portions of the body; a vanity ring in connection with the narrow portion of the heel body 45 extending upwardly therefrom; a section of leather glued to the rear and side walls of the heel body above the vanity ring and having its lower edge terminating at the vanity ring; a separate section of leather 50 secured to the rear and side walls of the heel body below the vanity ring, and a section of leather secured to the front side of the heel between the edges of the first-named sections of leather.

55 3. A shoe heel of the character described

comprising a heel body whose walls converge downwardly from the upper end for a portion of its vertical length, said walls flaring outwardly for the remainder of its vertical length to the lower end of the heel; 60 a vanity ring in connection with the narrowest portion of the heel body; a section of leather secured to the walls of the heel body above the vanity ring, and having its lower edge contacting with said ring; and a 65 separate section of leather secured to the walls of the heel body below the vanity ring and having its upper edge terminating at the lower edge of said ring; the outer surface of said ring being flush with the outer 70 surface of said sections of leather.

4. In a shoe heel of the character described, a heel body comprising a casting whose walls converge downwardly from the upper end for a portion of its vertical 75 length, said walls flaring outwardly for the remainder of its vertical length to the lower end of the heel; a flange integral with the heel body at the narrowest portion thereof; a section of leather secured to the walls of 80 the heel body above the flange, and having its lower edge contacting with said flange; and a separate section of leather secured to the walls of the heel body below the flange and having its upper edge contacting with 85 the lower side of said flange; the outer surface of said flange being flush with the outer surface of said sections of leather.

5. In a shoe heel of the character described, a heel body comprising a casting 90 whose walls converge downwardly from the upper end for a portion of its vertical length, said walls flaring outwardly for the remainder of its vertical length to the lower end of the heel; a flange integral with 95 the heel body at the narrowest portion thereof; a section of leather secured to the walls of the heel body above the flange, and having its lower edge contacting with said flange; a separate section of leather secured 100 to the walls of the heel body below the flange and having its upper edge contacting with the lower side of said flange, the outer surface of said flange being flush with the outer surface of said sections of leather; and a penetrable block embedded in the upper portion of the heel body to receive fasteners for holding the heel in connection with a shoe.

FREDERICK P. MARX.
